APPARATUS FOR MAKING PLATS

John B. Scheel, Washington, D. C.

Application November 10, 1948, Serial No. 59,226

10 Claims. (Cl. 28—2)

1

This invention relates to textile plats and to a method and device for making them.

It is an object of the invention to provide a device for making plats utilizing strips of textile material such as may be obtained from rags and remnants.

Another object is to provide such a device which is simple as to its parts, inexpensive to manufacture, light in weight and easy to operate so that it can be successfully used by children and convalescents as well as by skilled artisans.

A further object of the invention is to provide a device for making plats of various shapes, sizes, and stiffness.

Another object of the invention is to provide a device for forming plats that can be joined together by sewing or the like to fabricate rugs, mats, coverlets, or that can be provided with an integral backing for such uses or for use as buttons or badges.

A further object of the invention is to provide a plat composed of a strip of textile material wound in a substantially spiral configuration.

Another object is to provide a plat made up of end to end sewed strips of textile material wound in a generally spiral configuration having a backing composed of a fabric material or the like, with stitches binding together the convolutions of the plat and the backing.

A further object of the invention is to provide a method of winding strips of textile material into a spiral plat.

Another object is to provide a method of joining the convolutions of a spirally wound plat together while maintaining the shape of the plat.

These and other objects and advantages are provided by: a plat comprising a strip of textile material having substantially uniform width, the strips being disposed in a closely wound substantially spiral configuration, and means binding together the convolutions thereof to form a self-supporting unit; a method of making a plat comprising winding a strip of textile material of substantially uniform width into a substantially spiral form having contiguous convolutions and binding together the convolutions thereof while maintaining the shape of the plat; and a device for forming plats, as by winding strips of textile material in generally spiral configuration and thereafter sewing the wound strips together, which comprises a hub portion having an axial length substantially equal to the central thickness of the plat to be formed, a pair of end plates carried by the hub portion, the end plates being spaced apart to provide a zone substantially de-

2

fining the cross-sectional shape of the plat, at least one of the end plates having an opening therethrough positioned outside of the hub area through which joining means may be applied to the convolutions of the plat, and means releasably securing at least one of the end plates to the hub portion.

The invention will be more particularly described with reference to the illustrative embodiments thereof shown in the accompanying drawings in which:

Fig. 1 is an exploded view illustrating a plat-forming device in accordance with the principles of the invention;

Fig. 2 is an axial sectional view of the device of Fig. 1 in assembled condition;

Fig. 3 is a side view of a modified form of the device of the invention;

Fig. 4 is a side view of still another form of the device of the invention; and

Fig. 5 is a plan view of a mat formed from four plats made in accordance with the invention.

Referring to the drawings, in particular to Figs. 1 and 2, 10a and 10b are disc-like end plates which may be flat as shown or concave or convex. Concave or convex discs are used when finished plats are desired having cross sections greater or smaller at their hubs than at their peripheries. These plates are cut or molded from any suitable material such as wood, metal, paper, glass or plastic, the preferred material being a transparent plastic such as methylmethacrylate resin.

Plate 10a is provided with an integral boss 11a and handle 12a and with a central hub portion 13a having an axial length substantially equal to the central thickness of the plat to be formed. The outer surface 14a of hub 13a may be roughened as by knurling to form a friction-bearing surface that is securely gripped by a strip of material thus facilitating the winding of strips of textile material thereon. In the face of plate 10a a radial sewing slot 15a, extending from the hub 13a to the periphery of the plate, and a finger compression hole 16a are formed. The hub 13a and boss 11a are transversely drilled and threaded to receive a machine screw 25.

The plate 10b has a similarly drilled centrally located boss 11b, a corresponding sewing slot 15b and finger hole 16b.

The plat forming device is assembled for use by inserting the screw 25 through the drilled boss 11b of plate 10b and screwing it into the hub and boss 11a and 13a of disc 10a. Before the bolt is tightened the radial sewing slots 15a and 15b are aligned.

3

In the past "rag rugs" have been fabricated of textile strips by various methods which often required considerable skill, an expensive mechanical apparatus or a bulky frame or loom.

Rugs or mats have been made by using end to end sewed strips or remnants as woof or filling with a suitable yarn as a warp. They have also been produced by braiding strips of fabric sewed end to end, the resulting braid then being arranged and sewed into the desired shape and form. The hooked rug requires a base fabric through which the strips of material are "hooked" or interlaced.

In constructing plats for the fabrication of rugs and the like in accordance with the principles of the invention, textile strips are cut to the desired width from rags or remnants. The width of the strips is dependent upon the length of the hub 13a as this hub substantially defines the thickness of the plat to be formed. The strips may be sewed end to end before they are wound upon the hub or they may be wound successively one after the other. In either case a tightly wound substantially spiral configuration is formed consisting of a strip or strips of textile material. If a specific color array is desired the plates 10a and 10b should preferably be transparent allowing the operator to observe the growth of the convolutions of the plat. When the diameter of the plat for a given color has been reached, strips of the next succeeding color are then applied.

While winding the strips of material upon the hub the roughened surface 14a helps to prevent the material from slipping. Where a tighter plat is desired than the roughened surface 14a will allow, without slippage, pressure may be applied to the outside surfaces of the discs 10a and 10b. This pressure forces the discs closer together thereby gripping the wound portion of the plat. To facilitate this operation the drilled finger holes 16a and 16b are provided.

After completing the winding operation, the plat is sewed or bound together before it is removed from between the end plates. This is accomplished by using sewing slots 15a and 15b. In sewing the stitches are made to pierce the convoluted textile strips by sewing at an angle to the edges of the spirally wound strips thereby binding them together.

Having applied the desired number of stitch lines OA to the plat, bolt 25 is removed from hub 13a and boss 11b, end plate 10b is removed, and the stitched plat is slipped from the hub. It is then preferable to insert and bind a textile core or wadding 26 into the space left in the plat upon its removal from the hub 13a. This core forms the nucleus of the finished plat.

The finished plat may be used to fabricate rugs or mats, which, as shown for example in Fig. 5, may consist of four plats 20, 21, 22, and 23 joined together at their points of tangency. Plat 23 is of a modified form. It is constructed by cutting a disc of material 23a preferably slightly smaller in diameter than the plates 10a or 10b. This disc may be cut from such materials as textile fabric, stiff paper or cardboard, or wire mesh, or the stiffening disc may be a combination of such materials such as a wire mesh with a fabric backing. The disc is placed upon hub 13a and against one of the inside faces of either of the end plates prior to winding the textile strips upon the hub as hereinbefore described. During the stitching of the convolutions of the plat this disc 23a is

4

stitched firmly to one side of the plat, giving the latter added strength and rigidity.

The plat forming device shown in Fig. 3 has a modified plate 10c and hub 13c. The sewing slot 11c is V-shaped having reinforcing cross members or ribs 12c. The plate 10c is also provided with a series of small borings 14c which are used as finger holes when applying pressure to the plates. Successive strips may be inserted through these holes leaving a small tab or end to be held until a turn or two has been made on the hub or other strips have been rolled on. The elliptical hub 13c is used when making elliptical plats.

In the device shown in Fig. 4 the sewing slots 11d consist of diverging spiral openings extending from the outer extremity of the hub 12d to the periphery of the plate 10d. Within the diverging spiral slots 11d are reinforcing cross members or ribs 13d.

In making plats using the device of the present invention, the strip material is wound with sufficient tension to cause the edges of the plat to exert substantial outward pressure on the end plates of the device. This pressure is maintained during the sewing operation. Thereafter, when the finished plat is removed from the device, it has an inherent springiness tending to restore its original shape quickly after deformation. The plats are thus well suited for fabricating floor mats and floor coverings.

From the foregoing description it will be seen that the present invention provides a textile plat and a method and device for making the plate whereby the aims, objects, and advantages of the invention are fully accomplished.

I claim:

1. A device for forming plats, by winding strips of rag and the like in generally spiral convolutions and thereafter joining the wound convolutions of the strips together, which comprises a hub portion, a pair of end plates carried by said hub portion, said end plates being spaced apart to provide a zone substantially defining the cross-sectional shape of the plat, at least one of said end plates having an opening therethrough positioned radially outward of the hub area for applying joining means to the convolutions of the plat, at least one of said end plates being transparent, and means releasably securing at least one of said end plates to said hub portion.

2. A device for forming plats as defined in claim 1 wherein the opening for applying joining means to the convolutions of the plat is a radial slot extending toward the periphery of the end plate.

3. A device for forming plats as defined in claim 1 wherein the opening for applying joining means to the convolutions of the plat is a diverging slot extending toward the periphery of the end plate.

4. A device for forming plats as defined in claim 3 including plate stiffening members extending transversely across the diverging slot.

5. A device for forming plats by winding strips of textile material in generally spiral convolutions and thereafter joining the wound convolutions of the strips together, which comprises a hub portion, a pair of end plates carried by said hub portion, said end plates being spaced apart to provide a zone substantially defining the cross-sectional shape of the plat, at least one of said end plates having an opening therethrough positioned radially outward of the hub area for applying joining means to the convolutions of

the plat and another opening positioned between the hub and the periphery of the plate for applying finger pressure to urge the plat into frictional engagement with at least one of said end plates, and means releasably securing at least one of said end plates to said hub portion.

6. A device for forming plats, by winding strips of textile material in generally spiral convolutions and thereafter joining the wound convolutions of the strips together, which comprises a hub portion having an axial length substantially equal to the central thickness of the plat to be formed, said hub having a roughened surface to minimize slipping during the winding of said strips, a pair of end plates carried by said hub portion, said end plates being spaced apart to provide a zone substantially defining the cross-sectional shape of the plat, at least one of said end plates having an opening therethrough positioned radially outward of the hub area for applying joining means to the convolutions of the plat, said opening being a radial slot extending to the periphery of said end plate and another opening of substantially circular shape for applying pressure to urge the plat into frictional engagement with the end plates, and means releasably securing at least one of said plates to said hub portion.

7. A device for forming plats, by winding strips of rag and the like in generally spiral convolutions and thereafter joining the wound convolutions of the strips together, which comprises an end plate, a hub, a second end plate, and means releasably securing said end plates to said hub whereby said end plates are in face to face spaced relation to each other to provide a zone substantially defining the cross-sectional shape of the plat, at least one of said end plates having an opening therethrough positioned radially outwardly of the hub area for applying joining means to the convolutions of the plat and at least one of said end plates being transparent.

8. A device for forming plats as defined in claim 7 wherein the opening for applying joining means to the convolutions of the plat is a V-shaped slot extending toward the periphery of the end plate.

9. A device for forming plats, by winding strips of rag and the like in generally spiral convolutions and thereafter joining the wound convolutions of the strips together, which comprises a hub portion, a pair of end plates carried by said hub portion, said end plates being independently rotatable relative to each other and being spaced apart to provide a zone substantially defining the cross-sectional shape of the plat, at least one of said plates having an opening therethrough positioned radially outwardly of the hub area for applying joining means to the convolutions of the plat, said opening being formed in said plate without substantially reducing the surface thereof for contact with said convolutions of the plat to provide portions at either side of said opening extending about said hub capable of resisting the pressure of said wound plat, and means releasably securing at least one of said end plates to said hub portion.

10. A device for forming plats as defined in claim 1 wherein the opening for applying joining means to the convolutions of the plat is a substantially diverging spiral slot extending toward the periphery of the end plate.
